WINDOW SHADE

Filed April 9, 1927

Inventor
Samuel E. Snyder

By
Galph Burch
ATTORNEY

UNITED STATES PATENT OFFICE

SAMUEL E. SNYDER, OF BROOKLYN, NEW YORK

WINDOW SHADE

Application filed April 9, 1927. Serial No. 182,446.

This invention relates to new and useful improvements in window shades and more particularly to spring-actuated shades and an object of the invention is to provide a novel arrangement, whereby a shade of adjustable length may be suspended at any desired position in relation to the window opening in a manner to facilitate a fine and varied selection of light to the room.

10 A further object is to provide a suitable means, whereby a spring roller and its attached shade may be operably borne and in movable relation to the window opening.

15 A still further object is in the provision of a stationary spring roller adapted to actuate the further spring roller and its attached shade in relation to the window opening and at the same time having sufficient tension not to be effected by the tensioning of the spring 20 in the shade roller.

25 A yet further object is in the provision of the novel winding-cones which coil and uncoil the flexible connections from the shade-roller device in a manner to equalize the lever-age upon the roller in relation to the spring tension of the roller.

Another object of this invention is in the provision of a shade of the character described which is simple in construction, inexpensive to manufacture in consideration of the advantages offered; efficient and durable in service; positive in action and a general improvement in the art.

35 Other objects and many of the attendant advantages will be readily appreciated as the invention becomes better understood from a consideration of the illustrative embodiment of the same and for which purpose such descriptive drawing has been hereto appended, 40 wherein—

The single view is an elevation of a window with the invention attached.

Referring more in detail to the drawing in which similar reference numerals designate the corresponding parts:

45 It will be seen that the window 5 is normally covered by the shade 6 produced of suitable, tractable material 7 attached to the spring roller 8 in a manner to normally wind thereon by the tension of the spring. The

spring-roller 8 and its attached shade is operably suspended by the bar 10 which is of slightly greater length than the roller and has its end extremities angularly bent to constitute the depending ears 11 and 12 which engage and bear the roller trunnions 13 and 14. In the ear 11 is produced an orifice adapted to rotatably bear the rotatable trunnion 11 whilst in the ear 12 is an elongated slot adapted to receive the nonrotatable trunnion 14. 55 Through each of the trunnions 13 and 14 is produced an orifice which is adapted to receive a pin 15 or the like to the exterior of the engaging ears 11 and 12 in a manner to prevent sidewise movement and consequent disengagement of the roller 8 and its attached shade.

The shade 6 is suspended in adjustable relation to the window opening 5 by the cords 16 or the like which are attached to the stationary roller 17 in a suitable manner at 18 and depend therefrom to engage the eyes 19 which project from the shade-bearing bar 10.

70 The stationary spring roller 17 is rotatably borne by the common brackets 20 which are provided with ears 21 adapted to receive the rotatable trunnion 22 and non-rotatable trunnion 23 in common form. Mounted upon each end extremity of the roller 17 is a member 24 having the form of a frustum of a cone, hereafter termed cone, which cones have spiral grooves or threads 25 produced in their exterior surface and adapted to coil or uncoil the cords 16 in even, spaced turn in operation. Each of these cones 24 is also provided with an integral, annular flange 25 which is preferably of dimensions equal to the largest diameter of the cone and adapted to prevent over-winding of the cords 16 into the trunnions and consequent jam.

85 The cord 26 is secured to the eye 27 of the bar 10 in a manner to facilitate adjustment of the shade mechanism 6 in relation to the window opening 5, whilst the cord 28 is secured to the eye 29 of the filler-stick 30 at the free end of the shade material 7 in a manner to adjust the shade over the desired space of the window.

90 With this novel arrangement, it is obvious any desired portion of the window opening 100

5 may be covered, and that when the shade 6 is at the top of the window opening 5 and the tension spring of roller 17 is in relatively unwound condition, the cords 16 are 10 then engaging the cones 23 at their smaller diameter and nearer the axis of the roller. Therefore, the leverage is relatively less in proportion to the strength of the spring. Again, when the shade 6 is at the bottom of 15 the window opening and the tension spring of roller 17 is in relatively wound-up condition, then the cords 16 are engaging the cones 23 at their larger diameter and further from the axis of the roller, and the leverage is greater in proportionate relation to the strength of the spring. Accordingly by this novel cone arrangement, the leverage is equalized in proportion to the variation of the spring tension of roller 17.

20 It will be obvious from the foregoing description, that this invention is a great improvement in window shades and whilst the preferred embodiments have been disclosed, yet it is to be understood that minor details 25 in the construction, combination and arrangement of the cooperating elements may be resorted to within the scope of what is claimed without departing from the spirit of the invention.

30 What I claim is:

The combination with a window shade consisting of a spring roller and shade attached thereto, of a longitudinal bar having angularly bent ends adapted to operably support 35 said spring roller, a second spring roller revolvably mounted at the top of the window opening, conical sections attached to the ends of said second spring roller each having a spiral groove on its outer surface, cords suspending the ends of said bar from said conical sections, said cords having their uppermost ends connected to the largest ends of 40 said conical sections whereby the leverage upon the second spring roller is equalized in proportion to the tension of the spring thereof when in operation and flanges at the small 45 ends of said conical sections to prevent overwinding of said cords.

In testimony whereof I affix my signature.
50 SAMUEL E. SNYDER.
